UNITED STATES PATENT OFFICE.

ELIAL M. STAPLES, OF ELIZABETH, NEW JERSEY, ASSIGNOR TO THE SINGER MANUFACTURING COMPANY, OF NEW JERSEY.

PRESSER-FOOT-ACTUATING MECHANISM FOR SEWING-MACHINES.

SPECIFICATION forming part of Letters Patent No. 434,003, dated August 12, 1890.

Application filed May 19, 1890. Serial No. 352,291. (No model.)

To all whom it may concern:

Be it known that I, ELIAL M. STAPLES, a citizen of the United States, residing at Elizabeth, in the county of Union and State of New Jersey, have invented certain new and useful Improvements in Sewing-Machine Presser-Foot Mechanism, of which the following is a specification, reference being had therein to the accompanying drawings.

10 My invention relates to the presser-foot mechanism of sewing-machines, and has for its object to provide alternating pressers or alternately-lifted pressers, one or the other of which is always in contact with the work, the main presser swinging forward with the work when the latter is advanced by the feed and then being lifted so as to be returned by a spring, the auxiliary presser bearing on the work when the main presser is lifted and 15 then being lifted when the feed occurs and the main presser is swinging forward with the advancing work, thus specially adapting the machine for those kinds of work wherein the drag of the presser is objectionable in that 20 the work is liable to be injured by undue stretching.

In the drawings, Figure 1 is a side view, with the casing in section, of the head at the forward part of the bracket-arm of a Singer 25 sewing-machine embodying my invention. Fig. 2 is a front view of the head with the face-plate removed, and Fig. 3 is a view of the presser mechanism from the rear, or looking from the inside of the head outward.

30 The main rotating shaft A, having in the crank-disk a the crank-pin b, connected by a pitman b' with the needle-bar B, is the common construction with machines of this class.

C is the presser-bar, arranged in the usual 35 position in the head, and to the said bar is attached an angular arm or bracket c, provided with a roller-stud c', the said bar carrying at its lower end a small presser-foot c'', which will herein be termed the "auxiliary presser."

40 D is a flat bar arranged edgewise to the front of the head and fitted to slide up and down in suitable ways in the head, the said bar D being attached to a block d, through which the presser-bar C slides, the said block 45 having a lug or arm d' engaged by the lifter E.

The needle-bar-operating crank-pin b is provided with an arm b², having a roller-stud crank-pin b³ of slight eccentricity or small throw relative to the shaft A, said crank-pin b³ entering a slot f in the upper or vertical arm 55 of a bell-crank lever F, pivoted at f² on the block d, and having at the outer end of its lower or horizontal arm a slot f', receiving the roller-stud c' of the arm or bracket c, rigidly attached to the presser-bar C. 60

Pivoted at d² to the bar D is the swinging presser-bar G, carrying at its lower end the main presser g, which bears on the feed-dog h in the usual manner, the said dog being secured to the feed-bar H, connected 65 to and moved back and forth horizontally by the arm i of the feeding rock-shaft I, common to Singer machines. Bearing against the rear edge of the swinging bar G is a spring k, attached at its upper end to the bar D and 70 serving to return the said swinging bar to its normal position when it is lifted from the work after the feed has occurred.

The bar D is pressed downward by the usual depressing-spring m, bearing on the block d, 75 attached to said bar, and the pressure of the said spring is transmitted to the presser-bar C to depress said bar and its foot c² through the arm c and the bell-crank lever F, with which said arm is connected, said lever being pivoted on the said block, as heretofore stated.

From the construction of parts as above described it results that when the shaft A is rotated the crank-pin b³, working in the slot f² of the bell-crank lever F, will impart a rocking movement to the said lever. When the main presser G is on the work, the said lever will rock on the pivot f² as a fulcrum, thus raising the outer end of the horizontal 85 arm of said lever and lifting, through the arm c, the bar C and the auxiliary presser c'', carried by the latter. The main presser, carried by the swinging bar D, will then be moved forward with the work as the latter is advanced by the feed-dog, no other pressure, except that imparted by the main presser, being at this time on the work. When the feed 90 has been effected, the positions of the parts have been changed, so that the auxiliary 95 presser is now on the work, and the main presser is off the work. The lever F will then 100

presser is lowered on the work, and the bell-crank lever F will then rock on the stud c' as a fulcrum, thus lifting the bars D and G and the main presser carried by the latter bar, 5 and as soon as the said presser is released from the work it will be returned to its first position by the spring k. Thus as the machine continues in operation the pressers will rise and fall alternately, the main presser 10 swinging forward as the work is advanced by the feed and then being lifted and returned. The auxiliary presser is provided with a hole for the passage of the needle, and thus, as it is in contact with the work when the needle 15 rises, it serves as a stripper for the latter. Both pressers can be raised from the work together by the lifter E, when desired, the slot f of the vertical arm of the lever F being of sufficient length to permit the said lever to rise when 20 the pressers are thus elevated by the lifter.

I claim—

1. In a sewing-machine, the combination, with a vertically-movable bar and a swing- 5 spring-retracted main presser-foot pivoted therewith, of a bell-crank lever pivotally connected with said bar and having vertical and horizontal arms, a rotating device engaging the said vertical arm of said lever and a presser-bar carrying an auxiliary presser and provided with an arm 10 connected with the horizontal arm of the said lever, whereby the said pressers will be lifted alternately and the said main presser, after swinging forward with the feed, will be returned by its spring.

2. In a sewing-machine, the combination, with the presser-bar C, having the rigid arm c and carrying the auxiliary presser c², of the bar D, provided with the block d, the bell-crank lever F, having slotted vertical and horizontal arms, the latter connected with the said arm c, a rotating device, as crank-pin 15

b³, engaging the said slotted vertical arm, the swinging bar G, pivotally attached to the said bar D and provided with the main 45 presser g, and the returning-spring k.

3. In a sewing-machine, the combination, with the shaft A, having crank-disk a, provided with crank-pin b, having arm b², carrying crank-pin b³, of the presser-bar C, carrying the auxiliary presser c² and provided with the angular arm c, having stud c', the bar D, provided with the block d, the spring m, bearing on the said block, the bell-crank lever F, pivoted to the said block and having slotted 50 vertical and horizontal arms, the said vertical arm being engaged by said crank-pin b³ and the said horizontal arm by the said stud c', the swinging bar G, pivotally attached to the said bar D and carrying the main presser 60 g, and the returning-spring k.

4. In a sewing-machine, the combination, with the shaft A, having a crank-disk a, provided with crank-pin b, having arm b², carrying crank-pin b³, of the presser-bar C, carrying the auxiliary presser c² and provided with the angular arm c, having stud c', the bar D, provided with the block d, having the arm d', the spring m, bearing on the said block, the bell-crank lever F, pivoted to said 70 block and having slotted vertical and horizontal arms, the said vertical arm being engaged by said crank-pin b³ and the said horizontal arm by the said stud c', the swinging bar G, pivotally attached to the said bar D 75 and carrying the main presser g, the returning-spring k, and the lifter E to engage said arm d' and lift both pressers together.

In testimony whereof I affix my signature in presence of two witnesses.

ELIAL M. STAPLES.
